UNITED STATES PATENT OFFICE.

SEWARD B. ALDRICH, OF THURSTON, NEW YORK.

BELT SHORTENER AND TIGHTENER FOR THRASHING-MACHINES.

SPECIFICATION forming part of Letters Patent No. 330,542, dated November 17, 1885.

Application filed October 1, 1885. Serial No. 178,780. (No model.)

To all whom it may concern:

Be it known that I, SEWARD B. ALDRICH, a citizen of the United States, residing at Thurston, in the county of Steuben and State of New York, have invented a new and useful Improvement in Belt Shorteners and Tighteners for Thrashing-Machines, of which the following is a specification, reference being had to the accompanying drawings.

10 My invention relates to an improvement in belt shorteners and tighteners for thrashing-machines; and it consists in the peculiar construction and combination of devices that will be more fully set forth hereinafter, and particularly pointed out in the claims.

15 In the drawings, Figure 1 is an elevation of my invention applied to the driving-belt of a thrashing-machine. Fig. 2 is a detailed perspective view of the jack, the idle-pulley and snatch-block, the take-up, and tightening-rope. Fig. 3 is a detailed perspective view of the idle-pulley on the thrashing-machine, in use as a reel for the belt.

20 A represents a portable thrashing-machine of the usual construction, and B represents the usual portable steam-engine employed to furnish motive power to drive the machine. The fly-wheel B' of the engine is connected to the driving-pulley A' of the thrashing-machine by means of the usual endless belt, C. This belt is about sixty feet long, that being the usual distance at which the engine is placed from the thrashing-machine; but it very frequently becomes necessary to shorten the 25 distance between the engine and thrasher, and, where no other provision is made for shortening the belt, the latter has to be ripped at its connected ends and resewed when shortened.

30 40 The object of my invention is to provide means for shortening and tightening the belt without the necessity of ripping and resewing the same, and without having to move either the thrasher or the engine.

45 a represents a pulley on a shaft, b, journaled in front of the thrasher, out of the way, the pulley a being in line with the driving-pulley of the thrasher.

50 D represents a jack composed of a sill, d, and standards e. These standards are provided

on one side with a series of downwardly-inclined open slots or notches, f, in which the shaft or spindles g of an idle-pulley, h, may be journaled at any desired height from the ground. A snatch-block, i, is connected to 55 the spindles of pulley h by means of arms k.

When the belt is to be shortened, instead of only passing over the driving-pulley, as at full length, it is passed over the driving-pulley and under the idle-pulley a, forming a loop, 60 in which the pulley h is placed and drawn toward the engine until the belt is tight, and then placed in the jack, as shown at Fig. 1. To support the latter, a rope, l, has one end made fast to the front axle of the engine-frame, and its free end is then passed through one eye of a take-up device, m, made substantially in the shape of a figure 8, over the snatch-block, and then fastened to the other eye of the take-up. 65

To tighten the belt, it is only necessary to take hold of the rope at the take-up and pull from the thrasher. This can be most easily done when the machine is in motion. The take-up slips back freely on the rope and binds 70 thereon when released, as will be very readily understood.

When it is desired to remove the thrasher to another place, the belt can be reeled up on the pulley a, out of the way, as shown at Fig. 3. 80

Having thus described my invention, I claim—

1. The combination of the pulleys B' and A', the idle-pulley a, the endless belt connecting said pulleys and looped between pulleys A' 85 and a, and the idle-pulley h in the loop, journaled in a movable support, for tightening or shortening the belt, substantially as described.

2. The combination, with the pulleys B' and A', the idle-pulley a, the endless belt connecting said pulleys and looped between pulleys A' and a, and the idle-pulley h in the loop, of the jack having the series of open inclined slots to receive the spindles or shaft of pulley h, to support the latter, substantially as 90 described.

3. The combination of the pulleys B' and A', the idle-pulley a, the endless belt connecting said pulleys and looped between pulleys A' and a, the idle-pulley h in the loop and the 95 100

snatch-block attached thereto, the movable jacks in which pulley *h* is mounted, and the rope secured at one end to a fixed point and the other end passed through the snatch-block 5 and secured to a take-up, whereby the endless belt may be shortened or tightened, substantially as described.

4. The idle-pulley *a*, attached to a thrashing-machine, and adapted for use as a reel for

the endless driving-belt when the machine is 10 not in operation, substantially as described.

In testimony that I claim the foregoing as my own I have hereto affixed my signature in presence of two witnesses.

SEWARD B. ALDRICH.

Witnesses:

KEYES E. WHITMORE,
WILLIAM C. MASSEY.
